BOOK SUPPORT

Mark O. Hutchison, Oakland, Calif.

Application January 26, 1949, Serial No. 495

Term of patent 3½ years

(Cl. D33—2)

To all whom it may concern:

Be it known that I, Mark O. Hutchison, a citizen of the United States, and a resident of Oakland, county of Alameda, State of California, have invented a new, original, and ornamental Design for a Book Support, of which the following is a specification, reference being had to the accompanying drawing, forming part thereof.

I claim:

The ornamental design for a book support, substantially as shown.

MARK O. HUTCHISON.
